UNITED STATES PATENT OFFICE.

MORDECAI BROWN, OF HUNTINGTON, WEST VIRGINIA, ASSIGNOR TO HIMSELF, ROBERT T. ONEY, AND CHRIS YETTER, ALL OF SAME PLACE.

LIFTING-JACK.

SPECIFICATION forming part of Letters Patent No. 295,105, dated March 11, 1884.

Application filed December 29, 1883. (No model.)

To all whom it may concern:

Be it known that I, MORDECAI BROWN, of Huntington, in the county of Cabell and State of West Virginia, have invented certain new and useful Improvements in Lifting-Jacks; and I do hereby declare that the following is a full, clear, and exact description thereof, reference being had to the accompanying drawings, and to the letters of reference marked thereon, which form part of this specification, in which—

Figure 1 is an elevation of my improved lifting-jack, the pedestal or standard of which is shown in vertical section. Fig. 2 is an enlarged section taken horizontally through Fig. 1 in the plane indicated by dotted line $x-x$ thereon. Fig. 3 is a vertical section through the upper part of the jack, taken in the course of the dotted line $y-y$ on Fig. 2.

This invention relates to lifting-jacks of the screw kind, which are especially designed for use on railroads, but which are adapted for raising heavy weight generally; and it consists in combining a detachable lever-dog with a perforated hub on the jack-screw, and with collars loosely applied on this screw, which have a fulcrum-pin fixed to them, whereby the said lever-dog can be used either right or left handed, and an intermittent rotary movement can be imparted to the jack-screw without detaching the dog from its fulcrum, as will be fully understood from the following description, when taken in connection with the annexed drawings.

A designates the hollow standard of the jack, in the upper end of which is tapped the jack-screw B, having on its upper end the head C. These parts may be constructed in the usual manner common to the screw-jacks used on railroads and other places for lifting heavy loads.

On the upper part of the screw B, I rigidly apply a cylindrical hub, E, which has holes a diametrically through it, arranged at regular intervals apart, and above and below this hub I loosely apply on the threadless part of the screw-shaft B collars D D, which are rig-

idly secured together by pins G G', the former of which serves as the fulcrum for a lever-dog, F, used in turning the screw-shaft during the act of raising or lowering a weight. This lever-dog F may be of any desired length. It has formed on one end an enlarged head or dog, presenting a concave edge, b, adapted to fit snugly against the circumference of the perforated hub E, from which head projects a strong beveled tooth, d, adapted to enter any one of the perforations through the said hub. The head of the lever-dog F is also constructed with a strong hook, c, which is adapted to freely engage with the fulcrum-pin G, and at the same time allow the tooth d to enter one of the perforations a in the hub E, as shown clearly in Fig. 2.

For the purpose of preventing an accidental detachment of the lever-dog from its fulcrum-pin and hub during the act of raising a weight, I employ a safety-pin, e, which is removably applied to the collars D D, and located in such relation to said fulcrum-pin and hub that when this pin is in its place, as shown in Figs. 1 and 2, it will prevent the lever-dog from casually leaving its fulcrum-pin.

It will be observed that the lever-dog is reversible for either raising or lowering the screw-shaft, and that it is readily adjusted to the jack by first hooking it on the fulcrum-pin and moving the tooth into one of the perforations in the hub E. I now have a powerful leverage by which to turn the screw-shaft B.

The safety-pin e is inserted in its place through the collars D D after the lever-dog is applied to the jack.

By my invention, which is cheaply applicable to well-known screw-jacks, I dispense with ratchets and pawls and springs, and greatly simplify and exhaust the value of screw-jacks.

Having described my invention, what I claim as new, and desire to secure by Letters Patent, is—

1. The combination, with the jack-screw, its standard, and perforated hub, of the loose collars, the fulcrum-pin, and a lever-dog hav-

ing a hook and tooth, all constructed and adapted to operate substantially in the manner and for the purposes described.

2. A lever-dog adapted for a lifting-jack, 5 constructed as described, consisting of a long lever having formed on one end a fulcrum-hook and an engaging-hook, substantially as specified.

In testimony that I claim the foregoing as

my own I affix my signature in presence of two witnesses.

MORDECAI ^{his} X BROWN.
mark.
